No. 10,477.

PATENTED JAN. 31, 1854.

H. LULL.
SHUTTER HINGE.

UNITED STATES PATENT OFFICE.

HARVEY LULL, OF SOUTH COVENTRY, CONNECTICUT, ASSIGNOR TO H. LULL AND RICH'D. PORTER.

SHUTTER-HINGE.

Specification of Letters Patent No. 10,477, dated January 31, 1854.

To all whom it may concern:

Be it known that I, HARVEY LULL, late of Wheeling, in the county of Ohio and State of Virginia, but now of South Coventry, in 5 the county of Tolland and State of Connecticut, have invented certain new and useful Improvements in Self-Locking Hinges; and I do hereby declare the following to be a full, clear, and exact description of the same, 10 reference being had to the accompanying drawings, making a part thereof, in which—

Figure 1, represents the hinge as open and locked. Fig. 2 represents the hinge in its position when the shutter is drawn from 15 the wall sufficiently far, to unlock it, and Fig. 3, represents the hinge when the shutter is closed.

There are several varieties of shutter and door hinges, the greater portion of which in 20 being opened bring two inclined planes in action causing the shutter or door to rise,—the object being to cause doors especially to swing clear of the carpet. Some of these are provided with a fastening which is 25 formed of a separate piece. Another method is to make a series of planes, which admits of the door rising and falling several times in the act of swinging it open and shut. I do not lay claim to any of these hinges, for 30 they are almost useless for shutter hinges, for which purpose my hinge is especially designed.

It is well known that window shutters must swing into the window frames several 35 inches before they come to their seats, and to use either of the class of hinges before mentioned, would cause the shutter to rise up against the frame and bind, or else it must be cut away, which would admit rain snow

40 &c. My hinge allows the shutter to swing around horizontally until it almost reaches the wall when it drops and locks. This is one distinguishing feature of mine over other hinges. Again my hinge is composed 45 of but two pieces, each entirely of cast metal, while the others which are self locking are composed of three or more, and indeed many of those which work upon the planes use a friction roller to aid in causing one 50 half of the hinge to rise on the other half, which is expensive and very liable to become disarranged, as well as adding another piece to the hinge. This constitutes a second difference. But the most essential point of 55 difference between my hinge, and those here-

tofore essayed, consists in my being able to use a cast iron spindle with perfect safety, from the fact that when the shutter is opened and locked, the force of the wind tending to close the shutter is taken entirely 60 off the spindle and thrown upon two cast arms—and in opening or closing the shutter its weight is partially taken upon two square shoulders, thus relieving the spindle which is really but a directrix to the other 65 parts, without taking the weight of the shutter upon it. For this reason I can safely rely upon the cast iron spindle. I do not contend, however, that cast iron spindles have not been used, but I do contend that 70 they are liable to be broken by any sudden slamming of the shutter, as they heretofore had to sustain its entire weight. I do not assert that my invention consists of three 75 distinct differences between what has heretofore been done, and what I have done, but I claim, so combining these differences, as to produce in a hinge of two pieces, a very cheap, strong, and effective self locking hinge, which has not been done before. 80

The nature of my invention therefore consists in the so forming of a self locking hinge, cast in two pieces, as that a shutter hung thereon may swing open or shut on a horizontal plane, and lock when opened to 85 its limit, and so that also when locked open, the strain shall be taken off the spindle and thrown onto cam arms, and thus effectually relieve the spindle from the force of the winds. 90

To enable others skilled in the art to make and use my invention I will proceed to describe the same with reference to the drawings.

My hinge is cast in two pieces, of iron or any other suitable metal—each piece being identical in form with the exception that, one carries the spindle, the other the socket. Instead of forming the inclined planes on the shoulder of the hinge, as is heretofore done, I place them outside of the shoulder, and as remote from the center of the hinge as possible, placing one *b*, Fig. 3, on the arm or shank of the hinge, extending from the shoulder to the wing or plate, and projecting from two-thirds to three-fourths of its inclination from the face of the hinge. The other *a*, Fig. 3, is placed directly opposite, and extends the same distance from the center of the hinge, and faces, in the opposite 100 105 110

direction to that *b*. The inclination of the planes should be about forty-five degrees at the extreme outer end and approach the vertical as they come nearer the center of the hinge. The shoulder is formed with the half next the arm standing even with the top of the planes, and the other half cut down level with the bottom of the planes. The bottom half of the hinge inverted makes the top half by substituting the hole for the pivot. When a shutter hung on these hinges is thrown open, resting on the shoulders of the hinges, it neither passes over notches, nor up inclined planes, but swings freely around to a position nearly parallel with the wall where the support of the shutter passes from the shoulders *c*, *d*, Fig. 2, to the inclined planes, and the bottoms of the planes *A*, *A*, are brought to the tops of the planes *B*, *B*, as shown in Fig. 2, and the shutter is carried to the wall by its gravity on these inclined planes, and the hinge is locked as shown in Fig. 1, one half having dropped below its general position.

25 In closing the shutter, a slight force only

is necessary viz: to draw the shutter four or five inches to force it up the planes, when the support of the shutter is returned to the shoulders *c*, *d*, on which it rests and swings horizontally to its seat, entirely preventing 30 the planes from coming in contact as it closes as shown in Fig. 3.

Having thus fully described the nature of my invention what I claim therein as new and desire to secure by Letters Patent, is, 35

The so forming of a self locking shutter hinge, cast in two pieces, as that the blind or shutter hung thereon may swing open or shut on a horizontal plane, and lock when opened to its limit, and so that also when 40 locked open, the strain shall be taken off from the spindle and thrown onto cam arms, and thus effectually relieve the spindle from the weight or strain of the shutter, substantially as described.

HARVEY LULL.
